DRAFT GEARS FOR RAILWAY DRAFT RIGGING

Eric G. Forssell, Kenmore, N. Y., assignor to W. H. Miner, Inc., Chicago, Ill., a corporation of Delaware

Application July 18, 1955, Serial No. 522,597

5 Claims. (Cl. 213—45)

This invention relates to draft gears for railway draft rigging.

It is a main object of the invention to provide in a draft gear in which a resilient column is encased in a mechanical casing, an improved plunger for applying pressure to the column, which plunger includes means for securing the plunger in the casing, thereby to hold the gear together as a unitary structure.

Another object of the invention is to provide in a pressure applying plunger for a resilient column a keyway in which a key is mounted for movement into extended position and into engagement with the casing in which the column is encased.

Another object of the invention is to provide in a draft gear as set forth in the preceding objects, a front follower for the resilient column, which follower includes means interengaged with the plunger and key for holding the key in extended position and the plunger aligned in the casing, thereby to secure the gear together as a unit.

Further objects of the invention not specifically mentioned here will be apparent from the detailed description and claims which follow, reference being had to the accompanying drawings in which a preferred embodiment of the invention is shown by way of example and in which:

Figure 1 is a plan view of the assembled gear;

Figure 2 is a front end elevational view of the assembled gear;

Figure 3 is a cross sectional view of the gear casing, taken substantially along the line 3—3 of Figure 1, looking in the direction of the arrows;

Figure 4 is a longitudinal cross sectional view through the gear, taken substantially along the line 4—4 of Figure 2, looking in the direction of the arrows;

Figure 5 is a fragmentary cross sectional view through the gear, taken substantially along the line 5—5 of Figure 4, looking in the direction of the arrows;

Figure 6 is a cross sectional view through the plunger, taken substantially along the line 6—6 of Figure 4, looking in the direction of the arrows;

Figure 7 is a plan view of the plunger in operative position of the gear as shown in Fig. 1;

Figure 8 is a cross sectional view through the plunger, taken along the line 8—8 of Figure 7, looking in the direction of the arrows;

Figure 9 is a cross sectional view through the plunger, taken along the line 9—9 of Figure 7, looking in the direction of the arrows;

Figure 10 is an end view of the plunger;

Figure 11 is an edge elevational view of the key;

Figure 12 is a plan view of the key;

Figure 13 is an end view of the key;

Figure 14 is a plan view of the front follower;

Figure 15 is a side elevational view of the front follower;

Figure 16 is an end elevational view of the front follower;

Figure 17 is a cross sectional view through the gear

2

with the front follower telescoped therein preparatory to inserting the plunger into the casing; and

Figure 18 is a side elevational view diagrammatically illustrating the insertion of the plunger.

5 The gear of the present invention consists of a metallic casing A in which is disposed a resilient column B, stabilized by stabilizing separators C, and equipped with a front follower D against which the pressure applying plunger E abuts, the plunger carrying a key K by which the gear is held together as a unit.

The casing A, which is of rectangular cross section, consists of spaced apart essentially planar top and bottom walls 10 and 11, respectively, and spaced apart side walls 12 and 13. The casing is closed at its rear end by a rear wall 14 integral with the top, bottom and side walls. Adjacent the open front end of the casing, top and bottom walls 10 and 11 flare outwardly to form grooves 15 and 16, respectively, which grooves are closed at the open end of the casing by inturned flanges 17 and 18, best seen in Figure 17. Top and bottom walls 10 and 11 of the casing contain openings 19 extending through the walls and into the grooves 15 and 16, respectively.

20 The resilient column B, shown by way of example only, consists of solid rubber pads of known construction, with metal plates on the faces of the pads to which the pads are bonded. The column B is divided into groups by aligning separators C, also of known construction and consisting of web-like plates disposed between adjacent pads in the column B and having flanges in sliding engagement with the interior walls of the casing.

25 The front follower D, while of the same general construction as the aligning separator C, is modified by the inclusion of frusto-conical bosses 20 that extend forwardly from the platelike front wall 21 of the follower. Also extending forwardly from this wall 21 is a boss 22 that extends from end-to-end of the follower and contains at its ends triangular extensions 23. The rearwardly extending flanges 24 of the front follower contain rectangular 30 openings 25, best seen in Figure 15.

35 The plunger E consists of a frusto-pyramidal front section 30 reinforced by an internal wall 31 extending between the top and bottom portions of the section and by a short flangelike interior wall 32 that extends from end-to-end of the section and forwardly from the rear wall portion 33 thereof. This rear wall portion 33 extends but part way across the base portion of the plunger and contains frusto-conical sockets 34 located and spaced as will be seen best in Figure 8. Adjacent the lower end of 40 the plunger as it is positioned in the casing of the gear is a recess 35 that extends from end-to-end of the plunger and opens into the longer lower side thereof, this recess being defined at its forward boundary by a short flangelike wall 36 inwardly extending from the lower wall of 45 the frusto-pyramidal section and disposed parallel to the rear wall 33. Projecting outwardly from the longer side of the plunger at the top thereof, when the plunger is in operative position in the casing, are lugs 37. The interior wall 31 of the plunger contains a generally L-shaped opening 38 adjacent the recess 35.

50 The key K consists of a flat platelike portion 40 of thickness such as to enable it to fit in the recess 35, with its rearward face aligned with the rearward face of the wall portion 33. Upstanding from the platelike portion 55 of the key is a generally L-shaped wall 41 having a flange 42, which flange 42 is adapted to hook over the flangelike wall 36 of the casing, as will be seen in Figure 4. The end portions of the platelike wall 40 of the key are chamfered, as shown at 43, and lugs 44 project outwardly 60 from the longer side of the plate 40 opposite the wall 41.

65 In assembling the gear, the casing is positioned with its open end uppermost and the units of the resilient column

B inserted therein, with the aligning separators C inter-spaced as shown. When the column has been thus built up to the requisite number of units, front follower D is inserted and pressure applied to the front follower to telescope it into the casing sufficiently to align the openings 25 in the follower with the openings 19 in the casing. Keys 50 may then be inserted into the openings and serve to hold the plunger in telescoped position when pressure is removed therefrom.

The plunger, with the key K inserted therein, is then placed in the casing with its rear face at an angle to the follower and with the lugs 37 projecting into the grooves 15 in the upper wall 10 of the casing. The plunger is then rotated slightly counterclockwise, as seen in Figure 18, which brings the key K into engagement with the boss 22. A suitable tool 51 is then inserted through the openings 52 in the front wall of the plunger to move the key outwardly, thereby to move it off of the boss 22 and to position the lugs 44 on the key in the grooves 16 in the casing.

When the key has been moved into the position in which it is shown in Figure 4, the plunger may be rotated, counterclockwise as seen in Fig. 18, sufficiently to bring its rear wall 33 and the rear face of the key into engagement with the front face of the front follower D. The frusto-conical bosses 20 on the front follower projecting into the frusto-conical sockets 34 in the wall 33 of the plunger position that plunger and hold it with respect to the front follower. The engagement of the inner edge of the key plate 40 with the boss 22 prevents the key from being retracted into the plunger. Engagement of the flangelike wall 42 of the key with the flange wall 36 of the plunger prevents separation of the key and plunger. The chamfers 43 on the platelike portion 40 of the key abut against triangular extensions 23 of the boss 22, thereby to prevent longitudinal movement of the key.

The plunger having thus been positioned in the casing and against the front follower, pressure is applied to it to relieve the pressure on the keys 50 which are then removed, and as pressure is relieved on the plunger the column B expands, moving that plunger until the lugs 37 and 44 engage the flanges 17 and 18, respectively.

In operation, with the gear installed in the usual yoke and pocket of a draft rigging, pressure is applied to telescope the plunger into the casing to compress the resilient column which is maintained in alignment by the engagement of the flanges on the aligning separators and front follower with the walls of the casing. When the pressure is released, the column expands, moving the plunger into the position shown best in Figure 4.

Having thus complied with the statutes and shown and described a preferred embodiment of my invention, what I consider new and desire to have protected by Letters Patent is pointed out in the appended claims.

What I claim is:

1. In a draft gear for railway draft rigging, the combination with a metallic casing of rectangular cross section that is open at its front end and closed by a solid wall at its rear end, and a resilient column in said casing, which column is composed of rubber units; of a front follower engaging the front end of said column; flanges on said follower having sliding fit in the casing for guiding the follower; frusto-conical bosses on said follower pro-

jecting forwardly therefrom and located between the median line of the follower and one side thereof; a rectangular boss on said follower projecting forwardly therefrom, extending from end-to-end of the follower and located between said median line and the other side of the follower; a pressure applying plunger projecting outwardly from said follower through the open end of said casing; a rectangular rear wall on said plunger engaging said follower between said rectangular boss and the first mentioned side of the follower and containing frusto-conical openings into which said frusto-conical bosses project to position the plunger with respect to the follower; lugs on said wall projecting outwardly therefrom beyond the follower; a key engaging said follower between said rectangular boss and said other side of the follower; lugs on said key projecting outwardly therefrom beyond the follower, said casing containing inwardly opening grooves into which said lugs project; hook means on said key securing the key to the plunger; and flanges on said casing closing the front ends of said grooves and against which said lugs abut to hold the gear together as a unitary structure.

2. A device as specified in claim 1, in which the plunger contains an inwardly turned flange spaced from the follower and in which the key fits between said flange and the follower and has a forwardly extending wall that carries a flange that fits against the front face of the plunger flange to secure the key in position.

3. A device as specified in claim 2, in which the key abuts against the rectangular boss on the follower and is held thereby in the position with the lugs on the key projecting beyond the follower.

4. A device as specified in claim 2, in which the key extends from end-to-end of the plunger and follower, and contains chamfers at its ends which abut against triangular projections on the rectangular boss on the follower to prevent displacement of the key longitudinally.

5. In a draft gear for railway draft rigging, the combination with a metallic casing of rectangular cross section open at its front end and closed by a solid wall at its rear end and containing a resilient column composed of a plurality of rubber units divided into groups by flanged aligning separators that engage the walls of the casing to stabilize the column; of a front follower disposed against the front end of the column; a pressure applying plunger having a rectangular rear wall telescoped into the casing and engaging said follower; a pressure applying portion of said plunger extending forwardly from said base portion and beyond the open end of the casing; a recess in said plunger opening into the back thereof, into a longer side thereof, and into the ends thereof adjacent said longer side; a movable key disposed in said recess and extending beyond said longer side; lugs projecting beyond the other longer side of said rear wall; flanges projecting inwardly from the front end of said casing at the top and bottom thereof and engaging said lugs and key respectively to hold the gear together as a unit; and means including bosses projecting forwardly from the front face of said front follower and engaging said rear wall and key for maintaining the key extended into its flange engaging position.
